UNITED STATES PATENT OFFICE.

FREDERICK KOHNLE, OF DAYTON, OHIO, ASSIGNOR OF TWO-THIRDS TO
FRANK KOHNLE, OF ST. MARY'S, OHIO, AND LAWRENCE B. KOHNLE, OF CHICAGO, ILLINOIS.

DESIGN FOR A CANE.

SPECIFICATION forming part of Design No. 22,096, dated January 3, 1893.

Application filed September 16, 1892. Serial No. 446,102. Term of patent 3½ years.

To all whom it may concern:

Be it known that I, FREDERICK KOHNLE, a citizen of the United States, residing at Dayton, in the county of Montgomery and State of Ohio, have invented and produced a new and original Design for Canes, of which the following is a specification, reference being had to the accompanying drawing, forming part thereof.

The accompanying drawing is a representation of my newly designed cane.

The leading feature of my design consists in a spherical cane head formed as a representation of the world, and a stock or shank portion of the handle embellished with representations of the American eagle.

In the drawing A designates the handle portion of the cane consisting of a spherical head b and the shank or stem c. The spherical head b is ornamented with representations of continents suitably embossed or in low relief and the shank c is ornamented with representations of the American eagle.

B denotes the stock or cane proper.

I claim:

The design for a cane, substantially as herein shown and described.

In witness whereof I have hereunto set my hand this 13th day of September, A. D. 1892.

FREDERICK KOHNLE.

H. H. PRUGH,

J. E. CARSON.
